UNITED STATES PATENT OFFICE.

JOHN CROZIER AND LACHLAN STUART, OF MONTPELIER, VERMONT.

COMBINED HAT, COAT, AND UMBRELLA RACK.

No. 894,607.

Specification of Letters Patent.

Patented July 28, 1908.

Application filed October 19, 1907. Serial No. 398,188.

To all whom it may concern:

Be it known that we, JOHN CROZIER and LACHLAN STUART, citizens of the United States, residing at Montpelier, in the county of Washington and State of Vermont, have invented new and useful Improvements in a Combined Hat, Coat, and Umbrella Rack, of which the following is a specification.

Our invention relates to combined hat, 10 coat and umbrella racks.

One object of the invention is to provide a novel coin controlled means adapted to prevent the unauthorized removal of an article from the rack.

15 Another object of our invention is to provide a combined coat, hat and umbrella rack which is simple, durable and efficient, which comprises comparatively few parts, and which may be manufactured and sold at a 20 comparatively low cost.

With the above and other objects in view, the invention consists of the construction, combination and arrangement of parts hereinafter fully described, claimed and illustrated 25 in the accompanying drawings, wherein:

Figure 1 is a perspective view of a combined coat, hat and umbrella rack constructed in accordance with our invention. Fig. 2 is a central vertical sectional view of 30 the rack, the hat hook and locking lever therefor being in section. Fig. 3 is a sectional view on the line 3—3 of Fig. 2, looking in the direction indicated by the arrow. Fig. 4 is a sectional view on the line 4—4 of 35 Fig. 2, looking in the direction indicated by the arrow. Fig. 5 is a sectional view on the line 5—5 of Fig. 2, looking in the direction indicated by the arrow. Fig. 6 is a sectional view on the line 6—6 of Fig. 2, looking in the 40 direction indicated by the arrow. Fig. 7 is a vertical central section through the upper portion of the casing of the rack, illustrating the manner in which the locking levers of the coat hook and hat hook and umbrella arm 45 are adapted to be locked in closed position, and Fig. 8 is a detail perspective view of the inner end of the locking lever for the hat hook.

Referring to the drawings by reference 50 numerals, 1 designates the rear and 2 the front section of the casing of our improved rack. The sections are assembled so that the rear wall 3 of the section 2 forms a closure for the section 1, the section 2 being closed 55 by means of a removable plate 4. A horizontally disposed coat hook 5 is secured to

one of the side walls of the section 1, and a horizontally disposed umbrella arm 6 is secured to the opposite side wall of said section, said arm being provided with a recess 7 for the reception of the handle of an umbrella. A vertically depending hat hook 8 is secured to the bottom wall of the section 1. The coat hook 5 is offset, as at 9, to space the same from the support to which the rack is 60 secured, thereby enabling a coat to be readily and quickly applied to and removed from the hook.

A lever 10, which is pivotally secured to the side wall of the section 1, is adapted to 70 coöperate with the hook 5 to prevent the unauthorized removal of a coat therefrom, said lever being curved to adapt it to support a hand-bag. A lever 11 is pivotally mounted on the opposite side wall of the section 1, and is adapted to coöperate with the arm 6 to prevent the unauthorized removal of an umbrella therefrom. The levers 10 and 11 are horizontally disposed and are respectively provided with stems 12 and 13 75 which project into the section 1. A vertically disposed lever 14 is pivotally secured to the bottom wall of the section 1, and is adapted to coöperate with the hook 8 to prevent the unauthorized removal of a hat 80 therefrom. This lever is provided with a stem 15 which extends into the section 1 in the direction of the levers 10 and 11. A bracket 16 is secured to the upper end of the stem 15 and is provided with a pair of relatively spaced plates 17 adapted to receive 85 between them the ends of the stems 12 and 13 of the levers 10 and 11. The connection between the levers 10, 11 and 14 is such that when the lever 14 is moved in one direction 90 through the medium of a rod 18, all of the levers are moved into active positions, that is, into positions to prevent the removal of articles from the hooks and arm, and when the lever is moved in the reverse direction, 95 all of the levers are moved into inactive positions, that is, in positions to permit the removal of the articles. The rod 18 is secured to the bracket 16 and projects through the rear wall 3 and the plate 4 of the section 2, 100 the outer end thereof being provided with a head 19. An expandable coiled spring 20 is mounted upon the rod 18 between the bracket 16 and the plate 4, said spring being adapted to normally retain the levers in their inactive positions. A latch 21 is mounted 105 for vertical movement in guides 22, which

100

105

110

are secured to the inner face of the rear wall of the section 1. The latch 21 is retained in locking position by means of an expansible coiled spring 23, which is interposed between 5 the latch and the top wall of the section 1. When the latch is in locking position, its lower end is located between the upper end of the stem 15 of the lever 14 and the rear wall of the section 1, and retains the levers 10, 11 and 14 in their active positions. When it is desired to move the articles from the hooks and arm of the rack, the latch 21 is withdrawn, whereupon the levers will be moved into their inactive positions by the 15 spring 20, the latch 21 being supported in its withdrawn or inoperative position by the upper end of the stem 15, as fully shown in Fig. 2 of the drawings. When it is desired to secure the articles upon the hooks and arm, 20 the levers are moved into their inactive positions through the medium of the rod 18, whereupon the latch 21 moves into operative position and locks the levers in their active positions, as fully shown in Fig. 7 of the 25 drawings. The movement of the levers into their active positions compresses the spring 20, so that when the latch 21 is withdrawn, the levers are automatically moved into their inactive positions.

30 Access to the latch 21 is had through a key hole opening 24 in the plate 4 and an opening in the rear wall 3 of the section 2, the opening last referred to not being shown. A guard 25 is slidably mounted within the section 2 and is adapted to normally close the opening 24 to prevent access to the latch 21, said guard being held in its closing position by means of an expansible coiled spring 26, and is provided with a headed stem 27 by means 35 of which it can be operated to uncover the opening 24 when it is desired to gain access to the latch 21. The guard 25 is slidably mounted in a casing which is secured to the rear wall of the section 2 and which consists 40 of a bottom wall 28 and a front wall 29, one end of said casing being closed by a partition 30, which is secured to the rear wall of the section 2, and which provides a coin way 31. The section 2 is formed to provide a coin receptacle 32 by means of a partition 33, see Fig. 5 of the drawings. Access to the coin receptacle 32 can be had through a door 34. The movement of the guard by means of the spring 26 is limited by a block 35, and it is 45 adapted to be held in its closing position by means of a detent 36. The detent is pivotally secured to the rear wall 3 of the section 2 and its weighted end is adapted to engage a shoulder 37 formed on the guard 25. The 50 operating end of the detent 36 projects through an opening in the partition 30, so that a coin inserted through an opening 38 in the top wall of the section 2 will engage the same. The engagement of the operating end 55 of the detent 36 by a coin will tilt the detent

upon its pivot, thus releasing the guard 25. A leaf spring 39 is secured within the way 31 and is adapted to hold the coin between itself and the operating end of the detent 36, thus securing the detent in its inoperative position. 70

In practice, the device is set so that the levers 10, 11 and 14 are in their inactive positions, permitting a coat to be applied to the hook 5, an umbrella to the arm 6 and a hat 75 to the hook 8. After the articles have been applied, the levers are moved into their inactive positions through the medium of the rod 18, whereupon the latch 21 moves into its operative position and secures the levers 80 in their active positions. When the key, which when in applied position retains the guard 25 in its inoperative position, is removed, the guard is returned to its closing position by the spring 20, after which the detent 36 moves into its inoperative position and secures the guard in its closing position against movement. When the person to whom the articles belong desires to move the 85 same, he places a coin in the opening 38. As 90 the coin engages the operating end of the detent 36, the detent is moved upon its pivot into inoperative position, in which position it is held by the spring 39 clamping the coin between itself and the operating end of the 95 detent. The guard 25 is moved to uncover the key-hole opening 24 through the medium of the head 27, after which the key is inserted and operated to withdraw the latch 21. After the latch 21 has been withdrawn, the 100 levers 10, 11 and 14 are moved into their inactive positions by the spring 20. As the key retains the guard 25 in its inoperative position, and as the latch 21 is retained in its inoperative position by the stem 15 of the 105 lever 14, the apparatus is set for the next user.

Changes in the form, proportions and minor details of construction may be made within the scope of the claims without departing from the spirit or sacrificing any of the advantages of the invention. 110

Having fully described and illustrated our invention, what we claim is:

1. A device of the character set forth, including a casing, hooks secured to the casing, levers pivotally mounted upon the casing for coöperation with the hooks to prevent the removal of articles therefrom, said levers being provided with stems projecting into the 115 casing, a bracket secured to one of the stems for the reception of the other, a rod secured to one of the levers, said rod providing means by which the levers can be moved into active positions, a spring mounted upon the rod and adapted to normally retain the levers in inactive positions, and a latch adapted to retain the levers in active positions. 120

2. A device of the character set forth, including a casing, hooks secured to the casing, 125

levers pivotally mounted upon the casing for coöperation with the hooks to prevent the removal of articles therefrom, a bracket secured to one of the levers for the reception of 5 the other, so that the levers can be simultaneously moved into active or inactive positions, a rod secured to one of the levers and providing means by which the levers can be moved into active positions, a spring adapted 10 to retain the levers in inactive positions, and a latch adapted to retain the levers in active positions.

3. A device of the character set forth, including a casing, hooks secured to the casing, 15 levers pivotally mounted upon the casing for coöperation with the hooks to prevent the removal of articles therefrom, a bracket secured to one of the levers for the reception of the other, so that the levers can be simultaneously moved into active and inactive 20 positions, a latch adapted to retain the levers in active positions, a member adapted to prevent access to the latch, and a retractable member having engagement with said first 25 named member.

4. A device of the character set forth including a casing, a hook secured to the casing,

a lever pivotally mounted upon the casing for coöperation with the hook to prevent the removal of an article therefrom, said lever 30 being provided with a stem projecting into the casing, a rod secured to the stem and projecting from the casing, a spring mounted upon the rod between the stem and one wall of the casing to normally retain the lever in 35 inactive position, and a latch adapted to retain the lever in active position.

5. A device of the character set forth including a casing, hooks secured to the casing, levers pivotally mounted upon the casing for 40 coöperation with the hooks to prevent the removal of articles therefrom, a bracket secured to one of the levers for the reception of one end of the other so that said levers can be simultaneously moved into inactive positions, and a latch adapted to retain the levers in active positions.

In testimony whereof, we affix our signatures in presence of two witnesses.

JOHN CROZIER.
LACHLAN STUART.
